UNITED STATES PATENT OFFICE.

SPENCER C. ROGERS, OF OCEAN PARK, CALIFORNIA.

SHIPPING-TAG HOLDER.

1,405,006.

Specification of Letters Patent. Patented Jan. 31, 1922.

Application filed August 20, 1921. Serial No. 493,896.

To all whom it may concern:

Be it known that I, SPENCER C. ROGERS, a citizen of the United States, residing at Ocean Park, in the county of Los Angeles

5 and State of California, have invented a new and useful Shipping-Tag Holder, of which the following is a specification.

This invention relates to receptacles used for holding shipping tags and advice cards 10 in exposed position upon shipping containers, and relates particularly to holders of this nature from which the inserted cards cannot be removed, without destroying same, until the container upon which the holder 15 is mounted is opened by an authorized person.

It is an object of my invention to provide a shipping tag holder which will serve as a hasp to secure the cover of the container 20 upon which it is used in place.

It is a further object of my invention to provide in such a holder a latch means which will be of utility to fasten the free end thereof to the body of the container when 25 the container is in local transportation.

It is also a further object of my invention to provide a locking means for such a holder 30 where it will be handled by unauthorized persons.

It is a still further object of my invention to provide a latch for such a holder which will permit of extremely low manu- 35 facturing cost of the article.

Other objects and advantages will be made evident throughout the following.

Referring to the drawing which is for illustrative purposes only:

40 Fig. 1 is a perspective view of a container equipped with my invention.

Fig. 2 is a fragmentary section taken substantially upon a plane represented by the line 2—2 of Fig. 1.

45 Fig. 3 is a section taken on a plane represented by the line 3—3 of Fig. 1.

Fig. 4 is a fragmentary detail partially in section to illustrate the construction of the latch I employ.

50 Fig. 5 is a view of one of the shipping tags suitable for use with the embodiment of my invention shown in the drawing.

The container 11 upon which I herein demonstrate the utility of my invention is 55 one of the type suitable for transporting motion picture film and is comprised of a body

portion 12 having a cover 13 attached thereto by hinges 14. A grip 15 is provided for the convenient handling of the container in transportation.

A tag holder 18 is hinged to the front edge of the cover as shown at 19, this holder 18 being formed from a metal sheet 20 having portions punched therefrom to form openings 21 through which a shipping tag 65 22, held upon the underside of the holder 12 by the inwardly bent edges 23 and tongues 24, may be viewed.

I provide a latch means upon the free end of the holder 18 as shown in Fig. 4 of the 70 drawing. A centrally located tube 25 is formed by rolling the projecting edge 30 of the plate 19, and eyelets 31 are formed adjacent thereto by rolling metal tongues 32. A spring 35 is placed within the tube 25 75 and shouldered pins 36 and 37 are then inserted from each end through the eyelets 31. Punched metal discs or washers 40 and 41 are placed over the reduced portions of the pins 36 and 37 and are adapted to rest 80 against the shoulders upon the pins. The manner in which the washers are placed over the pins is illustrated at 42 in Fig. 4. The pin 37 is forced back against the action of the spring 35 and the washer 41 is inserted 85 between the end of the pin and the face of the eyelet 32, and the washer is brought to a position axially concentric with the pin 37 whereupon the reduced end 43 thereof is forced through the washer and the shoulder 90 44 upon the pin is brought to bear against the washer in a like manner to that shown at 44.

Upon the front of the body 12 of the container is mounted a plate 45 having projecting lugs 50 which are provided with holes 51. When the tag holder 18 is dropped from the position shown in Fig. 1 to a position against the side of the container, the lugs 50 project through slots 55 provided therefor in the tag holder, and the pins 36 and 37 may then be passed through the holes 50. From the plate 45 is also projected a lug 60 adapted to project through a slot 61 provided in the tag holder so that the tag holder may be locked against the container by locking a padlock through a hole 62 provided in the lug 60.

In ordinary transportation such as the delivery of films to local theaters, it is not 110 generally considered necessary to padlock the containers as they rarely leave the hands

of a person making the delivery or the consignee. Therefore, I provide a latch such as just described which may be easily and quickly disengaged by drawing the washers 5 40 and 41 inwardly with the thumb and forefinger.

With the use of my invention I accomplish a considerable saving in time over the methods now in use of attaching shipping tags and precautionary notices by the 10 use of paste, tacks, and other such means.

I claim as my invention:

1. The combination with a shipping container comprising a body member and a 15 cover member of: a shipping-tag holder hinged to one of said members and extensible over the other of said members; co-acting fastening means upon the free end of said tag holder and upon said member 20 over which said tag holder is extensible; and co-acting locking means associated with the free end of said tag holder and with said member over which said tag holder is extensible.

25 2. The combination with a shipping container comprising a body member and a cover member of: a shipping tag holder hinged to one of said members and extensible over the other of said members, said 30 holder having means formed thereupon to hold a shipping - tag; co - acting fastening means upon the free end of said tag holder and upon said member over which said tag holder is extensible; and co-acting locking 35 means associated with the free end of said tag holder and with said member over which said tag holder is extensible.

3. The combination with a shipping container comprising a body member and a 40 cover member of: a shipping-tag holder hinged to one of said members and extensible over the other of said members, said holder having means formed upon the underside thereof to hold a shipping tag and 45 having apertures formed therein through which said tag may be viewed.

4. The combination with a shipping container comprising a body member and a cover member of: a shipping-tag holder 50 hinged to one of said members and extensible over the other of said members, said holder having means formed upon the underside thereof to hold a shipping-tag and having apertures formed therein through 55 which said tag may be viewed; co-acting fastening means upon the free end of said tag holder and upon said member over which said tag holder is extensible; and co-acting locking means associated with the 60 free end of said tag holder and with said member over which said tag holder is extensible.

5. The combination with a shipping container comprising a body member and a 65 cover member of: a shipping-tag holder

hinged to one of said members and extensible over the other of said members, said holder having means formed upon the underside thereof to hold a shipping-tag and having apertures formed therein through 70 which said tag may be viewed; and co-acting locking means associated with the free end of said tag holder and with said member over which said tag holder is extensible.

6. In a shipping tag holder for shipping 75 containers, the combination of: a plate of suitable material adapted to be swingably attached to one of the members forming a container; means upon said plate for holding a shipping tag; fastening means upon 80 said plate to co-act with the fastening means upon another of said members forming said container; and co-acting locking means associated with said plate and co-actable with locking means associated with said secondly 85 named container member.

7. In a shipping tag holder for shipping 90 containers, the combination of: a plate of suitable material adapted to be swingably attached to one of the members forming a 95 container; means upon the underside of said plate for holding a shipping tag, and said plate having apertures formed therein through which said shipping tag is viewable; and fastening means upon said plate to co-act with fastening means upon another of said members forming said container.

8. The combination with a shipping container comprising a body member and a 100 cover member of: a shipping-tag holder 100 hinged to said cover member, said holder having means upon the underside thereof for holding a shipping tag and having holes formed therein through which said tag is 105 viewable; latch lugs extending from said body member adapted to pass through holes provided therefor in the free end of said holder; a tube formed upon the lower edge of said holder; eyelets formed upon said holder in alignment with said tube; shoul 110 dered pins in said tube adapted to engage said latch lugs, the reduced ends of said pins passing through said eyelets; washers mounted upon the reduced ends of said pins, said washers being operable against said 115 eyelets by said shoulders on said pins; and a spring acting between said pins to maintain same in extended position.

9. The combination with a shipping container comprising a body member and a 120 cover member of: a shipping-tag holder hinged to said cover member, said holder having means upon the underside thereof for holding a shipping tag and having holes formed therein through which said tag is 125 viewable; latch lugs extending from said body member adapted to pass through holes provided therefor in the free end of said holder; a locking lug extending from said body member adapted to pass through a hole 130

- provided therefor in the free end of said holder; a tube formed upon the lower edge of said holder; eyelets formed upon said holder in alignment with said tube; shoul- 5 dered pins in said tube adapted to engage said latch lugs, the reduced ends of said pins passing through said eyelets; washers mounted upon the reduced ends of said pins; said washers being operable against said eye- 10 lets by said shoulders on said pins; and a spring acting between said pins to maintain same in extended position.
10. A container comprising: a body mem- ber; a cover for said body member; a ship- 15 ping tag holder attached to one of said mem- bers; means for fastening said shipping tag holder to the other of said members; and means for holding a shipping tag in said holder in such a manner that said tag can- 20 not be readily removed when said holder is so fastened.
11. A container comprising: a body mem- ber; a cover for said body member; a ship- 25 ping tag holder attached to one of said mem- bers; means for fastening said ship- ping tag holder to the other of said mem- bers; and means so placed on the back of said holder that a shipping tag may be readily inserted in said holder but only
- when said holder is in its unfastened po- 30 sition.
12. A container comprising: a body mem- ber; a cover for said body member; a ship- 35 ping tag holder attached to one of said mem- bers; means for fastening said ship- ping tag holder to the other of said mem- bers; and means for holding a shipping tag in said holder in such a manner that said tag cannot be readily removed when said holder is so fastened, said holder hav- 40 ing openings formed therein through which said shipping tag may be read.
13. A container comprising: a body mem- ber; a cover for said body member; a ship- 45 ping tag holder attached to one of said mem- bers; means for fastening said ship- ping tag holder to the other of said mem- bers; and means so placed on the back of said holder that a shipping tag may be readily inserted in said holder but only 50 when said holder is in its unfastened po- sition, said holder having openings formed therein through which said shipping tag may be read.

In testimony whereof, I have hereunto 55 set my hand at Los Angeles, California, this 12th day of August, 1921.

SPENCER C. ROGERS.
